3 Claims. (Cl. 122—4)

This invention relates to a method of starting up a boiler, and particularly a method involving traversing a zone in the boiler with a sensing element detecting the local condition of the hot gases along the path of movement of the sensing element and utilizing the information thus obtained in control of the boiler during the starting up period. This application is a continuation of my copending application Serial No. 19,594, filed April 4, 1960, now abandoned, which in turn is a continuation of my application Serial No. 708,642, filed January 13, 1958, now abandoned which in turn is a division of my application Serial No. 640,641, filed February 18, 1957, now abandoned.

While in its broader aspects my invention is applicable to the scanning of furnaces of various types for various specific purposes my invention has especial utility when employed in connection with the starting up of a steam boiler and will be so described herein.

A conventional steam boiler has tubes and a superheater arranged in well known manner and means for firing the boiler such as a stoker or burners which when in operation cause hot gases to traverse the boiler in thermoconductive relation to the tubes and the superheater. The hot gases generated by the stoker or burners may first traverse tubes in the furnace chamber constituting the portion of the boiler known as the evaporator. The superheater for superheating steam beyond the evaporator may be disposed at the upper portion of the furnace chamber in the path of the hot gases as they move generally upwardly in leaving the evaporator. The gases may then pass to a stack and may impart heat to economizers en route to the stack as well known to those skilled in the art.

The evaporator is maintained full of water or other liquid being evaporated which effectively cools it to about the boiling point of the liquid at the pressure maintained, but the superheater contains only vapor, which is not an effective coolant, especially when vapor is not being withdrawn from the superheater as is the case when the boiler is being started up.

Furthermore, when the boiler is being started up and while no vapor is being withdrawn, substantially all the heat of combustion is being used to increase the temperature of the boiler setting, the evaporator and the superheater. It is important in relation to the life of the boiler and efficient operation thereof to bring the boiler gradually to its proper operating conditions without forming "hot spots" therein. Unlike the condition obtaining in normal operation, the heat released by the fuel is not principally absorbed by the evaporator at substantially a constant equilibrium temperature, and the temperature may rise to an excessive degree at one or more portions of the boiler and may result in damage, particularly to the superheater. The furnace chamber is of substantial width transversely of the direction of flow of the hot gases and absorbs heat unequally at different transverse portions thereof during start-up. The gases are not homogeneous across the furnace but vary in temperature and composition in streams flowing through the furnace.

For the practice of my invention I install furnace scanning apparatus in the furnace at or close to the super-

2

heater, preferably in the zone adjacent the evaporator but ahead (or up-stream) of the superheater. I preferably provide for traversing the zone adjacent the entrance to the superheater with a sensing element detecting a local condition of the hot gases along the path of movement of the sensing element. The stoker or burners is or are adjusted in response to the local condition so detected, bringing the furnace into proper operating condition. By scanning the gases from side to side local hot streams may be detected and the firing adjusted so that there will be no local hot spot endangering the superheater, which is without the protection of any cooling means.

My furnace scanning apparatus is, as above indicated, for detecting a condition in the furnace chamber. The condition may, for example, be temperature, or it may be the composition of the gases. In its broader aspects my invention is not limited with respect to what particular condition is detected, but for purposes of explanation and illustration my invention will be described in connection with furnace scanning apparatus for detecting the temperature across a furnace chamber.

I provide a method of starting up a boiler having tubes and a superheater and having firing means in the lower part of the boiler comprising initiating operation of the firing means, causing hot gases to traverse the boiler between opposed walls of the boiler in thermoconductive relation to the tubes and the superheater, moving across the boiler in a direction generally from one of said walls toward the other thereof, a sensing element detecting at each increment of such movement of the sensing element the local condition of the hot gases along the path of movement of the sensing element and in so doing traversing the hot gases in the region of the superheater with the sensing element and simultaneously detecting the location of the sensing element and adjusting the firing means in response to the local condition so detected. The condition detected may, for example, be temperature, or gas composition. The sensing element may and in certain cases preferably does traverse a zone adjacent the entrance of hot gases into the superheater.

The firing means may comprise burners arranged to fire inwardly into the lower part of the boiler or ranged across the boiler. Operation of less than all of the burners may be initiated. The hot gases may traverse the zone adjacent the entrance to the superheater and the sensing element may detect the local temperature or other condition of the hot gases along the path of movement of the sensing element, and the burners may be adjusted in response to the local temperature or other condition so detected. The sensing element in its continued traversing of the hot gases detects variations in the temperature or other condition of the gases as the burners are adjusted and the burners are readjusted from time to time in response to such variations while the boiler is being started.

To determine the composition of the furnace gases, a sampling tube may be mounted adjacent the hot junction of the probe connected through a hose and reel, similar to that provided for coolant, to a conventional gas analyzing device. Thus both the temperature and composition of the gas across the furnace may be determined together, the probe sensing substantially the complete condition of the furnace gases as the probe traverses the furnace.

Other details, objects and advantages of the invention will become apparent as the following description of a present preferred method of practicing the same and apparatus which may be used in practicing the same proceeds.

In the accompanying drawings I have illustrated a present preferred method of practicing the same and have

shown apparatus which may be used in practicing the same in which:

FIGURE 1 is a diagrammatic vertical cross-sectional view through a steam boiler;

FIGURE 2 is a diagrammatic elevational view, partly in vertical cross section, of furnace scanning apparatus applied to the steam boiler;

FIGURE 3 is a wiring diagram illustrating one wiring system which may be employed for operating the furnace scanning apparatus; and

FIGURE 4 is a fragmentary wiring diagram illustrating the wiring for the means for determining the position of the probe in the furnace chamber.

Referring now more particularly to the drawings, FIGURE 1 shows more or less diagrammatically a boiler comprising a vertically disposed furnace 2 of generally rectangular horizontal cross section having side walls 3 of refractory material at the inside surfaces of which are provided generally vertically disposed tubes 4 through which the water or other liquid to be evaporated is adapted to flow. The tubes 4 communicate with a header 5 forming a closed horizontal loop at the bottom and a header 6 forming a closed horizontal loop at the top. The headers 5 and 6 communicate through tubes 7 and 8 respectively with a drum 9 so that water is recirculated in the directions of the arrows *a* in FIGURE 1 and steam is withdrawn from the top of the drum 9 through tubes 10 and passes in the direction of the arrow *b* to a superheater 11. The superheater is shown in FIGURE 1 in outline defining the area in which it is installed without showing the banks of the tube of which it is comprised, it being understood that the superheater is of conventional construction. It is located in the path of the gases generally beyond the evaporating or steam generating section of the boiler.

In FIGURE 1 the firing means selected for illustration comprises burners set in the furnace wall but it is to be understood that any other conventional firing means such as mechanical stokers may be provided.

At their lower portions the walls 3 are provided with refractory lined burner openings 12 through each of which a burner 13 is adapted to discharge its flame inwardly. The burners are shown only diagrammatically because they may be of conventional construction and supplied with fuel and air for combustion as well known to those skilled in the art. The burners may be ranged in series both vertically and horizontally and thus are arranged as shown in FIGURE 1 in any desired firing pattern, as at the four corners for tangential flame projection or in horizontal rows in opposite walls for opposed-bank firing. FIGURE 1 indicates a vertical series of four such tangential or opposed-bank sets of burners along the walls 3 which would fire inwardly into the furnace. In "tangential" firing the burners 13 fire at an angle to the walls 3 so as to project their flames on a tangent to an imaginary circle about the vertical axis of the furnace, while in opposed-bank firing the burners project their flames substantially perpendicular to the furnace walls 3, both arrangements being well known and conventional in the art.

The burners 13 as shown are located in the lower part of the boiler and generate hot combustion gases which pass upwardly through the boiler including the superheater 11 and out through a duct 14 in which are disposed economizers 15 which may be of conventional construction to a stack, not shown, through which the gases are discharged to the atmosphere. The path of the gases is indicated by arrows *c* in FIGURE 1. The superheated steam is delivered from the superheater 11 through a pipe 16 in the direction of the arrow *d* in FIGURE 1. The header 6 and superheater 11 are surrounded by a refractory containing structure designated generally by reference numeral 17 which is integral and continuous with the furnace comprising the walls 3 and also with the duct 14. Thus continuous flow of hot gases

as indicated by arrows *c* is provided for. The portions of the tubes 4 in the lower part and the middle part of the furnace constitute the evaporating or steam generating portion of the boiler. A baffle 18 partially constricts the upper part of the furnace and controls the flow of gases to the superheater as shown in FIGURE 1. Solid residue such as slag is removed at the bottom through the cone 19.

The furnace scanning apparatus or probe is adapted to extend through one of the walls of the boiler comprising the furnace so as to scan the furnace chamber generally horizontally in a direction parallel to the walls 3. The probe is designated generally by reference numeral 20 (see FIGURES 1 and 2) and passes through an opening 21 in a wall 22 of the boiler. The probe is adapted to scan or traverse the furnace chamber in the region of or close to the superheater, preferably adjacent the entry portion of the superheater 11 as shown in FIGURE 1. It detects and indicates the condition of the furnace gases as they enter the superheater. The probe may be somewhat within the general superheater area as shown in FIGURE 1 or it may be outside that area, but for most sensitive control it is preferably installed adjacent the point where the hot gases enter the superheater. As pointed out above, the probe detects a condition in the furnace chamber at points along its path as it scans or traverses the furnace chamber and the burners are adjusted in response to the condition or conditions detected by the probe so that the boiler operates efficiently and without producing unduly overheated zones which may be detrimental to the tubes, the refractories or other portions of the installation.

Referring to FIGURE 2, an elongated support shown as in the form of an I-beam 23 is mounted outside the furnace chamber adjacent the opening 21 in the wall 22. One end of the I-beam may be supported from the wall by a bracket 24 as shown in FIGURE 2 and other suitable supporting means, not shown, for the I-beam may be provided. The I-beam 23 provides a straight horizontal track perpendicular to the wall 22 and directly above the opening 21. A carriage 25 is supported by the I-beam 23 through rollers 26 journaled in upward extensions 27 of the carriage, the rollers being disposed atop the respective bottom flanges of the I-beam. Thus the carriage 25 is adapted to move horizontally parallel to the I-beam and supported by the I-beam by the rollers 26 which are mounted for free rotation and turn as the carriage moves. The path of the carriage is perpendicular to the wall 22 and in alignment with the opening 21.

Connected with the carriage 25 and extending to the left therefrom viewing FIGURE 2 are concentric outer and inner conduits or tubes 28 and 29 respectively. The tubes 28 and 29 are in effect integral and spaced apart by suitable spacing means not shown to provide an annular space 30 therebetween. Within the inner tube 29 is disposed a thermocouple 31 which may be of conventional construction, comprising, for example, wires of dissimilar metal joined together at an end of the thermocouple forming the so-called hot junction designated by reference numeral 32. The hot junction 32 of the thermocouple projects out of the end of the tube 30 and also out of the end of the tube 28 through a fitting 33 which seals the ends of the tubes about the thermocouple. The opposite ends of the wires of dissimilar metals forming the thermocouple are disposed within the carriage 25 where they are respectively connected by wires with a voltmeter 34 which is mounted on the instrument panel in the boiler room. The connections to the voltmeter are shown purely diagrammatically in FIGURE 2, comprising a spring cord 35 and an electrical conduit 36. Each of the spring cord 35 and the electrical conduit 36 comprises two separate conductors. The conductors in the spring cord 35 are connected at one end with the hot junction wires of the thermocouple within the carriage 25 and are connected at the other end with conductors

in the electrical conduit 36 which in turn is connected with the terminals of the voltmeter 34. Thus the cold junction of the thermocouple is at the voltmeter and the respective wires of dissimilar metals of the thermocouple are electrically connected with the terminals of the voltmeter 34. A difference in temperature between the hot and cold junctions of the thermocouple produces an electrical potential or voltage therebetween which is measurable by the voltmeter. The voltage thus produced is proportional to the difference in temperature between the hot and cold junctions of the thermocouple. Thus the reading of the voltmeter 34 is a measure of the temperature at the hot junction 32 of the thermocouple, since the temperature at the cold junction of the thermocouple at the control panel is substantially constant. The voltmeter 34 may be calibrated in degrees of temperature.

Mounted on the I-beam 23 near the end of the I-beam which is relatively adjacent the furnace is an electric motor 37 which through reduction gearing 38 drives a sprocket 39. The motor 37 is of the reversing type. Adjacent the opposite end of the I-beam 23 is a bracket 49 which carries a sprocket 41 which is coplanar with the sprocket 39. A sprocket chain designated by the chain line 42 is dead-ended to the carriage 25 at each end of the sprocket chain as indicated at 43 and passes about the sprockets 39 and 41 so that the reach of the sprocket chain which is behind the carriage 43 viewing FIGURE 2 extends continuously between the sprockets 39 and 41. Rotation of the motor causes movement of the carriage along the I-beam through the action of the sprocket chain 42. The outer tube 28 is guided between rollers 44 so that the probe passes freely through the opening 21.

Coolant is adapted to be supplied to the annular space 30 between the tubes 28 and 29. The coolant may be compressed air which is supplied from a suitable source through a valve 45 to the hollow trunnion 46 of a reel 47. The hollow trunnion 46 communicates with a hose 48 which is wound upon the reel 47 and leads to the carriage 25 where it communicates with the annular space 30 between the tubes 28 and 29. Adjacent its left-hand end viewing FIGURE 2 the tube 28 is provided with lateral openings 49 through which the coolant escapes. The reel 47 is spring operated to reel up the hose 48 which the carriage 25 moves toward the right viewing FIGURE 2 and to pay out the hose when the carriage moves toward the left. The spring cord 35 similarly contracts when the carriage moves toward the bracket 49 and stretches out when the carriage moves toward the left away from that bracket.

Carried by the shaft which carries the sprocket 41 is a potentiometer 50 which is electrically connected through an electrical conduit 51 with a position indicator in the form of a voltmeter 52 (see FIGURES 2 and 4). The current for the potentiometer is supplied through leads 53, a rheostat 54 being provided for zero adjustment of the potentiometer. The movable potentiometer contact is operated when the carriage 25 moves along the I-beam 23 and consequently when the hot junction 32 of the thermocouple traverses its path in the furnace chamber. The result is a change in voltage which can be read on the voltmeter 52. That voltmeter thus determines the position of the hot junction of the thermocouple at all times. The voltmeter 52 may be calibrated directly for the position of the hot junction of the thermocouple. Thus the two instruments 34 and 52 make it possible to determine the temperature at each point along the path of travel of the hot junction of the thermocouple in the furnace chamber since the temperature at each instant is shown by the instrument 34 and the position of the hot junction of the thermocouple at each instant is shown by the instrument 52.

Switches 55, 56, 57 and 58 are provided along the path of the carriage and are adapted to be operated by a finger or lug 59 projecting upwardly from the carriage.

The control mechanism will now be described with

particular reference to FIGURE 3. The motor 37 is shown at the lower left-hand corner of the figure. It is a three-phase motor and operates in either direction, being reversed by reversing any two of the three electrical connections to the motor. The switches 55, 56, 57 and 58 are shown at the bottom of FIGURE 3. The switch 55 is a limit switch at the extended or farthest inward position of the probe. When the limit switch 55 is operated by the finger 59 on the carriage 25 it opens one contact and closes another. The switch 56 is a limit switch at the retracted or farthest outward position of the probe. When the limit switch 56 is operated by the finger 59 on the carriage 25 it opens one contact and closes another. The switch 57 is for controlling the valve 45 through a solenoid 60. The valve as above explained controls the admission of coolant to the hose 48. The switch 57 is a sustaining contact single pole switch open and closed by the finger 59; in other words, the switch 57 is closed except when the carriage moves to the right viewing FIGURE 2 so that the switch is opened by the finger 59. When the carriage moves back to the left viewing FIGURE 2 the switch 57 is again closed. The switch 58 is a limit switch at the parked position of the carriage. It contains two normally closed contacts which open when the carriage reaches parked position. A signal device is shown at 61. The signal device may be for making an audible or visual signal or both being shown as a bell or gong.

There is shown at 62 a solenoid operated relay with two normally open contacts 63-64 and 65-66, both of which close when the solenoid is energized. There is shown at 67 a solenoid operated relay with two normally open contacts 68-69 and 70-71 which close when the solenoid is energized. There is shown at 72 a solenoid operated relay with two normally open contacts 73-74 and 75-76 and two normally closed contacts 77-78 and 79-80. Reference numeral 81 designates generally a reversing switch which operates selectively by means of solenoids 82 and 83 to close the three-phase motor circuit in forward or reverse connections to the motor 37. Solenoids 82 and 83 are not connected in the three-phase circuit but are wired in a single phase control circuit in which the auxiliary contacts presently to be described operated by the same solenoids are also connected.

At the right of FIGURE 3 is shown a four-button push button station, all of the buttons being of the momentary contact type for return to normal position when the operator removes his finger from the button. The button to extend the probe is designated 84 and has one normally closed contact 85-86 and two normally open contacts 87-88 and 89-90. The button to retract the probe is designated 91 and has one normally closed contact 92-93 and two normally open contacts 94-95 and 96-97. The button to stop the probe is designated 98 and has one normally closed contact 99-100. The button to park the probe is designated 101 and has one normally open contact 102-103.

Assuming that the solenoid of the relay 72 is not energized and that the contacts 77-78 are therefore closed, pressing either the extend button 84 or the retract button 91 momentarily closes the circuit from the line L-1 through contacts 87-88 or 94-95, as the case may be, and the normally closed contacts 77-78 to the solenoid of the relay 62. This causes the contacts 63-64 in the relay 62 itself to close and thereby electrically latches the relay 62 in position with its solenoid energized through the normally closed contacts 99-100 of the stop button 98. The relay 62 also closes contacts 65-66 connecting the line L-1 to both terminal 104 of the limit switch 55 and the terminal 105 of the limit switch 56, which condition will be maintained until such time as the solenoid of the relay 62 is de-energized as would occur upon pressing the stop button 98. The solenoids 82 and 83 of the reversing switch 81 are connected in circuits between the limit switches 55 and 56 and the opposite line L-2. The

solenoid 82 controls normally open contacts 109—110 and normally closed contacts 107—108. The solenoid 83 controls normally open contacts 111—112 and normally closed contacts 128—129. In the circuit to solenoid 82 is a normally open contact 89—90 of the extend push button 84 and in like manner in the circuit to the solenoid 83 is a normally open contact 96—97 of the retract push button 91. These contacts are also selectively closed as either of the push buttons 84 and 91 is pressed whereby to momentarily selectively energize one or the other of the solenoids 82 and 83 as the case may be through the various other contacts closed at that time. In the circuit containing the solenoid 82 these are the normally closed contacts 128—129 which would be opened by the solenoid 83, contacts 79—80 of the relay 72, contacts 104—105 of the limit switch 55 and contacts 92—93 in the retract button 91. Similarly, in the circuit containing the solenoid 83 these are the normally closed contacts 107—108 which would be opened by the solenoid 82, contacts 85—86 in the button 84, contacts 119—120 in limit switch 58 and contacts 104—105 of limit switch 56. As soon as either of the solenoids 82 and 83 is energized it closes a shunt circuit (109—110 in circuit with the solenoid 82 and 111—112 in the circuit with the solenoid 83) around the push button contact and thus electrically latches itself in energized position, permitting release of the push button. When one of the solenoids 82 and 83 is thus energized it closes its respective contacts 113 to the motor which is thereby cause to start in one direction and to continue to run in the same direction until stopped or reversed as will presently be described. Thus if the stop button 98 should be pressed, opening contacts 99—100 and thereby de-energizing the solenoid of the relay 62, that relay will return to its normal position breaking the contacts 65—66 to both of the limit switches 55 and 56 thereby de-energizing either of the solenoids 82 and 83 and closing all three-phase circuits to the motor 37. Each of the extend push button 84 and the retract push button 91 has one normally closed contact in addition to the two normally open contacts to which reference has been made above. Those normally closed contacts are wired in the circuits between the limit switches 55 and 56 to the reversing switch solenoids so as to open whichever of those circuits may have been closed when the other circuit is closed by pressing that particular button. Thus the normally closed contacts 92—93 of the retract button 91 are in series between the limit switch 55 and solenoid 82 while the normally closed contacts 85—86 of the extend button 84 are in series between the limit switch 56 and the solenoid 83. Thus these push buttons provide manual control of reversal of the motor at any time.

When the movement of the carriage has been started as above described and the carriage moves to the position in which the finger 59 engages one of the limit switches 55 and 56, that limit switch opens its normally closed contacts (104—105 of limit switch 55 or 105—114 of limit switch 56) and thereby de-energizes the solenoid 82 or the solenoid 83 as the case may be. This in turn causes current to cease to flow to the motor 37. At substantially the same time the normally open contact (104—115 of limit switch 55 or 105—116 of the limit switch 56) is momentarily closed. As shown in FIGURE 3 these contacts are connected in parallel with the contacts 89—90 of the extend button 84 and 96—97 of the retract button 91 providing for manual control or reversal of the carriage, so that the operation of the limit switches has the same effect and energizes the other solenoid (82 or 93 as the case may be) of the reversing switch 81 to reserve flow of current to the motor. The first effect of reversal of flow of current to the motor is, of course, to slow it down and bring it to a quick stop, whereafter the motor runs in the opposite direction. This stopping and reversal of the motor is to be effected within a very short distance in the travel of the carriage. The

whole reversal takes place substantially at the location of the limit switch 55 or 56 as the case may be, the carriage not traveling through the limit switch in normal operation. Thus when the apparatus has been set in motion by pressing either the extend button 84 or retract button 91 the carriage is set in motion in a certain direction and travels toward the opposite limit switch which automatically reverses it, this back and forth motion continuing and causing the probe to traverse and retrace the furnace chamber until it is stopped in some way.

When it is desired to shut down the operation of the furnace scanning apparatus the park position button 101 is pressed. This momentarily closes the contacts 102—103 in direct circuit between the line L-1 and the solenoid of the relay 73, the opposite pole of which solenoid is connected to the line L-2. When the solenoid of the relay 72 is energized it closes contacts 73—74 in series through contacts 117—118 in limit switch 58 to the line L-1 and thereby latches itself in energized position. At the same time contacts 75—76 in relay 72 are closed, directly energizing the circuit to the solenoid 83 through the normally closed contacts 119—120 in the limit switch 58, 85—86 in the extend button 84 and 107—108 in the reversing switch 81 which are closed only when the solenoid 82 is de-energized. At the same time normally closed contacts 77—78 and 79—80 in relay 72 are opened which de-energize the solenoid of relay 62 and opens the contacts 65—66. It will be seen that if at the time the park button 101 is pressed and all this takes place the probe should be moving in the extend direction its travel will be reversed, while if the probe happens to be moving in the retract direction its travel will continue in the same direction under control of the circuit which is changed as has been described. However, the limit switch 56 is no longer in circuit to the solenoid 83 but instead the limit switch 58 through the normally closed contacts 119—120 will control the point in the travel of the carriage at which the solenoid 83 will be de-energized. Therefore the retraction of the probe will continue until the detent 59 on the carriage 25 engages the limit switch 58. This not only opens the contacts 119—120 as has been mentioned but also opens the contacts 117—118 in circuit to the solenoid of the relay 72, causing the latter to be de-energized, which again restores contacts 77—78 to their normally closed condition, which was the condition assumed at the beginning of this description.

If at any time the temperature detected and indicated by the indicator 34 should be excessive, as, for example, more than 1000° F., or whatever is considered a hazardous temperature condition under the circumstances, the contacts 121—122 in the temperature indicator will close and this completes a circuit from the line L-1 to the solenoid of the relay 67, closing contacts 68—69 and contacts 70—71. The contacts 68—69 are connected in parallel with the contacts 102—103 of the park position button 101 so that if they are closed the same operations are effected as described above when the park push button is pressed and the temperature probe is withdrawn automatically to parked position. Closing the contacts 70—71 in the relay 67 completes the circuit from the line L-1 to the terminal 123 of the alarm device. The opposite terminal 124 of the alarm device is connected to the line L-2. Hence the alarm will be actuated when the solenoid of the relay 67 is energized.

For control of the supply of cooling air to the probe the valve 43 is operated by the solenoid 69. The single pole sustaining contact type switch 57 is mounted between the limit switches 55 and 58 in the path of the finger 59 so as to be tripped by that finger as the carriage passes the switch 57. This switch contains the contacts 125—126 which are closed by travel of the carriage as it moves in the extend direction and are opened by the carriage as it moves in the retract direction toward parked position. When the carriage is extended and the con-

tacts 125—126 are closed a circuit is completed to the solenoid 60, thereby opening the valve 45 and admitting air to the hose 48. As the carriage is retracted to parked position the contacts 125—126 are opened and the solenoid 60 is de-energized, shutting off the supply of air. The switch 57 is mounted on the I-beam 23 in a position which will shut off the flow of air as the probe is retracted but before it has been entirely removed from the furnace and has entered the wall box 127 (see FIGURE 2).

While I have illustrated a present preferred method of practicing the invention and have shown apparatus which may be used in practicing the same it is to be distinctly understood that the invention is not limited thereto but may be otherwise variously practiced within the scope of the following claims.

I claim:

1. A method of starting up a boiler having tubes and a superheater and having firing means in the lower part of the boiler comprising initiating operation of the firing means, causing hot gases to traverse the boiler between opposed walls of the boiler in thermoconductive relation to the tubes and the superheater, moving across the boiler in a direction generally from one of said walls toward the other thereof a sensing element detecting continuously at all points in the path of movement of the sensing element in the space across the boiler between said walls the local condition of the hot gases and simultaneously detecting the location of the sensing element, evidencing at a single point on the instrument panel in the boiler room the location of the moving sensing element at each moment as the sensing element moves across the boiler and evidencing at a point adjacent the first men-

tioned point on the instrument panel in the boiler room the local condition of the hot gases at each location evidenced at the same moment at said single point and adjusting the firing means in response to the local condition so detected.

5 2. The method of claim 1 in which the sensing element detects the local temperatures of the hot gases and the firing means are adjusted in response to the temperatures so detected.

10 3. The method of claim 1 in which the sensing element traverses a zone adjacent the entrance of hot gases into the superheater and detects temperature variations in said zone and the firing means are adjusted in response to the variations in temperature thus detected.

UNITED STATES PATENT OFFICE
CERTIFICATE OF CORRECTION

January 14, 1964

Patent No. 3,117,556

Sanford S. Bowles

It is hereby certified that error appears in the above numbered patent requiring correction and that the said Letters Patent should read as corrected below.

Column 3, line 31, for "of the tube" read -- of tubes --;
column 6, line 53, for "normaly" read -- normally --; line
69, after "both" insert -- the --; column 7, line 29, for
"cause" read -- caused --; line 69, for "93" read -- 83 --;
line 70, for "reserve" read -- reverse --, column 8, line
6, for "motiton" read -- motion --.

Signed and sealed this 14th day of July 1964.
